Des. 222,894
Patented Jan. 25, 1972

222,894

SCAFFOLD PLANK

Charles Polk Taylor, Magnolia, Ark., assignor to Southern Extrusions, Inc., Magnolia, Ark.

Filed May 18, 1970, Ser. No. 23,044

Term of patent 14 years

Int. Cl. D25—99

U.S. Cl. D54—1

FIG. 1

FIG. 1 is a perspective view of the new design for a scaffold plank, taken from above and showing a side and an end thereof;

FIG. 2 is an elevational view of one side thereof, broken away for ease of illustration, the other side elevational view (not shown) being identical;

FIG. 3 is a plan view, broken away for ease of illustration looking upwardly at the bottom thereof; and

FIG. 4 is an elevational view of one end thereof, the other end elevational view (not shown) being identical.

I claim:

The ornamental design for a scaffold plank, as shown and described.
